UNITED STATES PATENT OFFICE.

ANTON F. SCOW, OF CHICAGO, ILLINOIS.

IMPROVEMENT IN BASKET-FORMS.

Specification forming part of Letters Patent No. **138,765**, dated May 13, 1873; application filed February 10, 1873.

To all whom it may concern:

Be it known that I, ANTON F. SCOW, of Chicago, in the county of Cook and State of Illinois, have invented a new and useful Improvement in Basket-Forms, of which the following is a specification:

The nature of the present invention consists in a hinged clamp which is combined with adjustable standards for holding the basket-bottom in position for weaving the splints, and in a band which surrounds the lower end of the form, and is provided with clamps for holding the standards in place, as the whole is hereinafter fully described and shown.

In the drawing, Figure 1 is a longitudinal elevation of my improved basket-form; Fig. 2, a top or plan view of the same.

A B represent the foundation or frame which supports the form and my improvements, it being made of wood or other suitable material, and of any size required. C C represent adjustable standards, which slide through the frame A B, and are provided with slots E for receiving the set-screws D, which hold the standards at the required height for different-sized basket-forms. A metal clamp, X, is pivoted to one of the standards C at F so as to swing up or down, and its other end is provided with a slot, I, as shown by dotted lines, to receive a set-screw, H, which holds the clamp to the standard, the slot allowing the clamp to be adjusted to or from the form M. This form is pivoted to a standard, V, in the usual manner, so as to rotate, and the bottom J of the basket is held closely to it by a spring-clamp, K, which passes through the curved clamp X. If, however, the clamp X is made of spring

metal, the spring-clamp K may be substituted by any suitable stationary bearing to press against the bottom J. The lower end of the form is provided with a band, O P, corresponding in thickness to the thickness of the standards of the basket, for the purpose of preventing the ends of said standards from catching the hands and clothes of the operator, and for the purpose of providing a suitable support for the catches T, which slide back and forth in a groove made transversely in said band for the purpose. Only one sliding catch is shown in the drawing, but the number of catches in practice corresponds to the number of basket-standards. By this means the making of a hole through the basket bottom J is avoided, while at the same time the band O P prevents the lower end of the splints from catching the clothing or hands of the operator, and forms a convenient support for the latches which hold the splints.

To change the devices for a larger form or smaller one, the set-screws D must be loosened, which will permit of the standards C being raised or lowered. The bottom is held to the form M by means of set-screw H and clamp X, the clamp X being swung over back on pivot F when the form M is to be removed.

I claim—

The curved clamp X with stationary or adjustable standards C, when used to hold the bottom J to form M, substantially as and for the purpose set forth.

ANTON F. SCOW.
